B. H. PELTON

CONCRETE MIXER AND CONVEYER

Filed May 4, 1926

FIG. 4

FIG. 3

FIG. 2

INVENTOR.
BENJAMIN H. PELTON
BY *A. B. Bowman*
ATTORNEYS.

UNITED STATES PATENT OFFICE.

BENJAMIN H. PELTON, OF CARLSBAD, CALIFORNIA, ASSIGNOR TO B. H. PELTON, JR., OF CASPER, WYOMING.

CONCRETE MIXER AND CONVEYER.

Application filed May 4, 1926. Serial No. 106,616.

My invention relates to a concrete mixer and conveyer adapted to be used for conveying concrete in the construction of large concrete structures, such as buildings, bridges, 5 or structures where concrete is to be conveyed a considerable distance.

Heretofore in the construction of concrete buildings, bridges and the like, the concrete for the construction was mixed at or conveyed by elevator to a central point and distributed from the central point by dump trucks or by tubular conveyers or chutes. The use of ordinary tubular conveyers or 10 open chutes has been found ineffective and impractical in that the finer and coarser aggregates separate from each other and from the thin concrete, making an uneven pour in the concrete structure, often to the extent of considerably weakening the structure at certain 15 portions.

The objects of my invention are: first, to provide means whereby concrete is received from the mixer or elevator and conveyed to the desired point and continually mixed, 20 when being conveyed; second, to provide a positive tubular conveyer whereby concrete or other materials may be conveyed from a central point to any position desired and in any reasonable direction, either downwardly, 25 on a level, or upwardly from its central point of distribution or supply, or to the side thereof; third, to provide a sectional positive conveyer which may be made in any length desired and easily directed to the point desired; 30 fourth, to provide novelly constructed positive conveyer extension sections; fifth, to provide a novel means for operatively connecting the conveyer screws of the conveyer sections with each other; sixth, to provide novel 35 means for effectively coupling the conductor portions of the conveyer sections; seventh, to provide a conveyer of this class which may be operated at a relatively slow speed for conveying material thereto and also at a relative- 40 ly high speed for flushing the conveyer; eighth, to provide as a whole a novelly constructed mixer and conveyer of this class, and ninth, to provide means of this class which is simple and economical of construction pro- 45 portionate to its functions, durable, efficient, and which will not readily deteriorate or get out of order.

With these and other objects in view, as will appear hereinafter, my invention consists of certain novel features of construction,

combination and arrangement of parts and portions, as will be hereinafter described in detail and particularly set forth in the appended claims, reference being had to the accompanying drawings and to the characters of reference thereon, which form a part of this application, in which:

Figure 1 is a fragmentary side elevational view of my mixer and conveyer in one form of construction, showing its relation with a 60 concrete mixer and showing certain parts and portions of the conveyer broken away and in section to facilitate the illustration; Fig. 2 is an enlarged fragmentary sectional elevational view, showing the connection or joint 65 between two sections of the conveyer; Fig. 3 is an end view of one of the conveyer sections, taken at 3-3 of Fig. 2, and Fig. 4 is a fragmentary view in plan, showing the drive and 70 gear shifting means.

Like characters of reference refer to similar parts and portions throughout the several views of the drawings.

The one or normally stationary end of my 75 concrete mixer and conveyer is mounted on a platform 1, which is preferably in the form of a portable platform or truck. On and above the platform or truck 1 is mounted another, shiftable platform 2, the one end of which is pivoted on the platform 1, as indicated by 3 in Fig. 1. The opposite end of the platform 2 is 80 vertically adjustable by means of a screw or screws 4, the lower end or ends of which is pivoted on the platform 1. The screw 4 extends through the threaded member 5, which 85 is pivoted on a horizontal axis on brackets 6.

On the platform 2 is mounted the power plant 7, which may be in the form of an internal combustion engine. On the platform 2 is also mounted a pair of brackets 8, at the 90 upper ends of which is supported the conveyer drum or casing 9. In this drum or casing is revolubly mounted a conveyer screw 10, the one end of the shaft 10^a of which is revolubly mounted in the head 9^a of the casing, and the 95 opposite end of which is revolubly mounted in the journal portion of the inwardly offset bracket 11, which is in the form of a spider having three legs supported by the wall at the open end of the casing 9, as shown in Figs. 1 and 2. On the end of the shaft 10^a extending beyond the head 9^a are provided drive-gears 100 12 and 13, which are adapted to be driven respectively by drive-gears 14 and 15. The latter gears are mounted on a sleeve 16, which is 105 110

shiftably mounted on the shaft 7^a of the engine 7. The sleeve 16 is adapted to be shifted on the shaft 7^a by means of a gear shift lever 17. For normal operation of the mechanism, 5 that is, when materials are desired to be conveyed thereby, the lever 17 is shifted to the solid line position, shown in Fig. 4, which connects the drive-gear 14 with the gear 12.

At the upper portion of the casing or drum 10 9 is provided an upwardly flaring chute or spout 18 for receiving concrete from the chute 19 of the concrete mixer 20. Concrete, however, may be discharged into the chute 18 from an elevator, if desired. The one end of the 15 conveyer casing 9, or the portion of the casing around the chute 18, is raised from the upper portion of the conveyer screw 10, as indicated by 9^b in Fig. 1, so that large stones or other aggregates will not be crushed or jammed 20 between the upper portion of the conveyer screw and the casing. The opposite end of the casing 9 from the head 9^a is circular, as shown in Fig. 3.

The open or discharge end of the conveyer 25 casing 9 may be extended to any desired length by the conveyer tube sections 21. One end of the tube sections 21 are flared outwardly, as indicated by 21^a. These outwardly flared portions 21^a receive the open ends of 30 the adjacently positioned conveyer sections. Said tubes or sections are secured together at their adjacent ends by means of bolts 22, there being preferably three in number. These bolts extend through lugs 23 near the 35 ends of the tubes or sections. The holes in these lugs are preferably tapered from their opposite sides, or the same may be merely enlarged, to receive the bolts 22 when positioned at various angles. The opposite sides of the 40 lugs 23 are rounded to provide even bearing surfaces for the bolt-heads and nuts, as shown best in Fig. 2. The tubes or tube sections may be coupled together in a straight line or at slight angles, as shown in the drawings, the 45 practical maximum of these angles being between ten and fifteen degrees. The outwardly flared portion at one end of the tubes and a beveled portion at the adjacent end of the adjacently positioned tube provide a relatively close joint between the two sections or 50 tubes of the connected conveyer sections. Slight openings between the connected ends of two tubes may be readily closed by tightly taking up the bolts 22, the adjacent ends of 55 the tubes being slightly distorted by such taking up to provide a reasonably close joint.

At the opposite ends of the tube sections 22 are secured inwardly offset spider brackets 11, similar in construction to the one previously 60 referred to. In these brackets 11 are revolvably mounted the opposite ends of the shaft 24^a of the conveyer screw 24. To the opposite ends of the shafts 24^a of the conveyer screw, as well as to the end of the shaft 10^a extending 65 through the brackets 11, are secured trans-

versely slotted universal joint members 25. The adjacently positioned universal joint members 25 of connected conveyer sections are operatively connected by an intermediate universal joint member 26 having lug portions 26^a at its opposite ends and positioned at right angles to each other. These lug portions 26^a extend into the transverse slots or grooves of the universal joint members 25, as shown best in Fig. 2. The spider brackets 11 75 are offset inwardly to provide space for the universal joint members 25; the ends of the arms of the brackets 11 being secured as near the ends of the tubes of the conveyer sections as possible to provide a maximum space for the blades or conveyer portions of the conveyer screws. The conveyer portions of the conveyer screws near the open ends of the tubes are cut out at their hub portions, as indicated by 10^b and 24^b in Fig. 2, to clear the 80 journal portions of the brackets 11 and to permit the outer portions of the conveyer screws to extend as far as possible toward the end of the tubes. Said cut out portions of the conveyer screws are preferably reinforced at 85 their back sides by reinforcing members 27, as shown in Figs. 2 and 3.

The several sections of the sectional conveyer may be supported from below on suitable structures or suspended from above by 90 means of cables 28, shown in Fig. 1.

When desiring to flush the conveyer for cleaning the same, the lever 17 is shifted to the dotted line position, which connects the gears 13 and 15, permitting the conveyer 100 screws to be rotated at greater speeds.

It will be here noted that although my mixer and conveyer is particularly adapted for conveying concrete and simultaneously mixing the same, the same may be adapted for conveying many other classes of materials, and though I have shown and described a particular construction, combination and arrangement of parts and portions, I do not wish to be limited to this particular construction, combination and arrangement, but desire to include in the scope of my invention, the construction, combination and arrangement substantially as set forth in the appended claims.

Having thus described my invention, what I claim as new and desire to secure by Letters Patent is:

1. In a means of the class described, a pair of conveyer casings adapted to be connected at various angles at one of their ends, inwardly offset spider brackets mounted within and at the adjacent ends of said casings, conveyer screws revolvably mounted at one of their ends in said brackets, and universal joint means connecting the adjacent ends of said conveyer screws between the offset portions of said brackets.

2. In a means of the class described, a pair of conveyer casings adapted to be connected 130

- at various angles at one of their ends, inwardly offset spider brackets mounted within and at the adjacent ends of said casings, conveyer screws revolubly mounted at one of their ends in said brackets, and universal joint means connecting the adjacent ends of said conveyer screws between the offset portions of said brackets, the adjacent ends of said conveyer screws extending outwardly beyond the inwardly offset portions of said brackets.
3. In a means of the class described, a conveyer casing having an open ended cylindrical portion, another open ended cylindrical conveyer casing slightly funneled at one end, said funneled portion positioned over the cylindrical end portion of said first mentioned casing, means for rigidly securing said conveyer casings together at various angles, conveyer
- 5 screws revolubly mounted in said casings, and flexible means connecting said conveyer screws.
4. In a means of the class described, a conveyer casing having an open ended cylindrical portion, another open ended cylindrical conveyer casing slightly funneled at one end, 25 said funneled portion positioned over the cylindrical end portion of said first mentioned casing, means for rigidly securing said conveyer casings together at various angles, conveyer screws revolubly mounted in said casing, and universal joint means connecting the adjacent ends of said conveyer screws.
- 10 In testimony whereof, I have hereunto set my hand at Carlsbad, California, this 23rd day of April, 1926.
- 15 BENJAMIN H. PELTON.
